JAMES W. BRYCE, OF BLOOMFIELD, NEW JERSEY, ASSIGNOR TO INTERNATIONAL TIME RECORDING COMPANY OF NEW YORK, OF ENDICOTT, NEW YORK, A CORPORATION OF NEW YORK.

CLOCK-CONTROLLED ELECTRIC CIRCUIT.

1,260,317.

Specification of Letters Patent. Patented Mar. 26, 1918.

Application filed July 21, 1917. Serial No. 181,963.

To all whom it may concern:

Be it known that I, JAMES W. BRYCE, a citizen of the United States, residing at Bloomfield, in the county of Essex and State of New Jersey, have invented certain new and useful Improvements in Clock-Controlled Electric Circuits, of which the following is a full, clear, and exact description.

This invention relates to electrical systems in which an electrical circuit or circuits are controlled by contacts or terminals which are actuated or controlled by a clock; as for example electrical clock systems in which one or more subordinate clocks are caused to run in unison with a master clock by means of current impulses sent periodically from the master clock. A clock which is an accurate timekeeper has but little energy to spare beyond that necessary to drive its own train, and hence, as is well understood, the contact mechanism actuated by the clock must be light and delicate. This is no great disadvantage so long as the voltage across the contacts, is low, but with higher voltages destructive arcing occurs at the contacts. It is unnecessary to enlarge upon the drawbacks entailed by the injury thus caused, but it may be said that in clock systems a clean make and break of the circuit is a matter of prime necessity.

My present invention is designed to provide a system in which high voltages may be used in the operating circuit without arcing at the clock contacts and without requiring any increase in the size or mass of the latter. To this and other ends the invention comprises the novel features and combinations hereinafter described.

In the accompanying drawing, Figure 1. Shows in side elevation part of a clock movement adapted for use in my invention.

Fig. 2. Is a rear view of the same.

Fig. 3. Is a diagram illustrating an embodiment of the invention, and

Fig. 4. Is a similar diagram illustrating another embodiment.

In the construction illustrated the circuit which is controlled by the clock contacts includes the scape-wheel arbor 10, to or from which current is led by means of a light brush 11 fixed at one end on an insulating support 12 and having its other end bearing on a slip-ring 13 fixed on said arbor.

The latter also carries a light contact in the form of an arm 14 having an inclined face 15 on its outer or free end to wipe on a light-spring contact 16 which is insulated by means of a non-conducting support 17. It will then be seen that once in each revolution of the scape-wheel 18 the circuit in which the contacts 14—16 are included will be closed and opened as the contact 14 engages and passes the other. This is not, however, the main circuit of the system, but is a local circuit which is so associated with the main circuit as to control the latter in a satisfactory manner. For this purpose the contact 14 is connected by wire 19 to one side of a source of current 20, Fig. 3, the other side or terminal of which is connected to the contact 16 through a relay magnet 21 and a resistance 22. Hence when the circuit is closed current flows from battery 20 through wire 19, contact 14, contact 16, resistance 22, wires 23, 24, relay magnet 21, and wires 25, 26 back to the battery. Being thus energized the relay magnet draws its armature 27 over against contact 28, thereby laying a shunt across contacts 14—16, with the result, that the current now flows from battery 20 through wire 29 to the subordinate clock or clocks or other device or devices (diagrammatically indicated at 30) which the master clock is intended to control. From 30 the current flows through wire 31, relay armature 32, contact 33, wire 34, armature 27, contact 28, wires 35 and 24, relay magnet 21, and wires 25, 26, back to the battery. The electrical instrumentalities (not shown) in the device or devices 30 are thus energized, and, as will be seen, the contacts 27—28 are held closed by the continued energization of magnet 21, which is itself in the main circuit just traced. The contact 14, actuated by the scape-arbor, now passes the contact 16, but without sparking since the resistance 22 causes the major portion of the current to take the path of lesser resistance through contacts 32—33, 27—28.

For the purpose of breaking the main circuit through the device or devices 30 when the current has caused the electrical instrumentalities thereof (not shown) to perform their functions, the scape-arbor 10, Figs. 1 and 2, is provided with an additional contact arm 36, coöperating with another spring contact 37, these contacts being similar in all

respects to contacts 14 and 16 already described. Contact 36, however, is displaced angularly in rear of contact 14. In other words, contacts 36—37 are behind contacts 14—16 in time, as it were, so that the former will operate only after contacts 14—16 have engaged and separated. Contact 36 is connected to wires 23, 24, 35 and contact 37 is connected through resistance 38 to a second relay magnet 39, which is in turn connected to wires 25 and 26. Now when contact 36 engages contact 37 current flows not only through the main circuit (traced above) but also through an auxiliary circuit from wire 35 through wire 40, contacts 36—37, resistance 38, wire 41, magnet 39, and wires 42, 26, back to the battery; it being understood that the resistance 38 is of such value as to allow current to flow in sufficient amount to energize relay magnet 39. The latter then draws its armature 32 away from contact 33, thereby breaking the main circuit and the branch circuit just traced through contacts 36—37. Hence there is now no voltage across the latter, with the result that there can be no arcing when they separate. Also, the breaking of the main circuit at contacts 32—33 deenergizes relay 21, thereby opening contacts 27—28. Consequently, although when relay 39 is deenergized as described its armature 32 may immediately swing back against contact 33 it does not thereby re-establish the main circuit. The system is therefore left in its normal condition, as shown in Fig. 3; except, of course, that the contacts 14 and 36 have passed the contacts 16, 37, and are now below the latter instead of above.

In the embodiment illustrated in Fig. 4 the contacts 14^a, 36^a, are in parallel, and the relay 21^a has two armatures, 27^a, 27^b, co-operating with contacts 28^a, 28^b, respectively. When contacts 14^a—16^a are closed a local circuit is formed in which current flows from the source 20 through wires 43, 44, contacts 14^a—16^a, resistance 22^a, wires 45, 46, magnet 21^a, and wires 47, 48, back to the battery 20. Armatures 27^a, 27^b are then drawn over against their contacts and the main circuit is established from source 20 through wire 49, devices 30^a, wire 50, armature 32^a, contact 33^a, wire 51, armature 27^a, contact 28^a, wires 52, 46, magnet 21^a, and wires 47, 48, to the source. When clock contact 36^a engages contact 37^a an auxiliary circuit is formed in which current flows through wire 53, contacts 36^a—37^a, resistance 38^a, wire 54, armature 27^b, contact 28^b, wire 55, magnet 39^a, and wires 56, 48, back to the source. Magnet 39^a, being thus energized, draws its armature away from contact 33^a, thereby breaking the main circuit, which deenergizes magnet 21^a and allows armatures 27^a, 27^b to swing back from their contacts. There is then no voltage across contacts 36^a—37^a, and conse-

quently the latter can separate without possibility of sparking.

In both forms it will be seen that the first function is energization of the main circuit relay (21, 21^a) by the closing of clock contacts 14—16, 14^a—16^a, thereby closing the main circuit, through the relay, at the normally open contacts. Next, the first clock-contacts are opened, followed by closing of the shunt or second clock contacts 36—37, 36^a—37^a, by which the shunt-circuit, across the main circuit relay 21, 21^a, and across contacts 27—28, 27^a—28^a, is closed and the shunt relay, 39, 39^a, is energized. The latter opens the normally closed main-circuit contacts, thereby opening the main circuit. The main-circuit relay, 21—21^a, is thus deenergized, permitting its contacts, 27—28, 27^a—28^a, 27^b—28^b, to open, which in turn deprives the shunt-circuit of current and thereby permits the second clock-contacts to open without any potential across them. It will be further observed that in both forms the first clock-controlled contacts, 14—16 and 14^a—16^a, are connected across the normally open main-circuit contacts which are closed by the main-circuit relays 21 and 21^a; and that the second clock-controlled contacts, 36—37 and 36^a—37^a, and the relays 39, 39^a, are connected across the respective relays 21, 21^a, and across the respective contacts 27—28, and 27^a—28^a, 27^b—28^b.

It is to be understood that the invention is not limited to the embodiments herein specifically illustrated and described but can be embodied in other forms without departure from its spirit as defined by the appended claims.

I claim:

1. In a system for the purpose described, in combination, a main circuit, a source of current therefor, a relay in the main circuit and having normally separated contacts also in said main circuit, a local circuit through said relay, clock-controlled contacts in the local circuit to close and open the same, a second relay, having normally closed contacts in the main circuit, an auxiliary circuit through the second relay, and clock-controlled contacts in the auxiliary circuit and behind the first named clock-controlled contacts whereby to operate after the latter.

2. In a system for the purpose described, in combination, a main circuit having a pair of normally open contacts and a pair of normally closed contacts; a local circuit having means for closing the normally open contacts; clock-controlled contacts in the local circuit to close and open the latter; an auxiliary circuit having means for opening the normally closed contacts; clock-controlled contacts in the auxiliary circuit to close and open the latter and timed to operate after the first-mentioned clock-controlled contacts.

3. In a system for the purpose described, in combination, a main circuit having a pair of normally open contacts and a pair of normally closed contacts, a relay in the 5 said main circuit to close the normally open contacts, a pair of normally open clock-controlled contacts in parallel with said normally open main-circuit contacts whereby the latter will be closed by energization of 10 the relay when the clock-controlled contacts are closed, a shunt-circuit across said relay and clock-controlled contacts, a relay in the said shunt circuit to open the said normally closed contacts and thereby open the main 15 circuit, and normally open clock-controlled contacts in the shunt circuit and behind the first-mentioned clock-controlled contacts in time, to close the shunt-circuit and cause energization of the second relay.
- 20 4. In a system of the kind described, in combination, a main-circuit, a pair of nor-
- mallly open and a pair of normally closed contacts therein, a clock controlled shunt-circuit around the normally open contacts, an electromagnet therein for closing said 25 contacts, an electromagnet in another clock controlled shunt to the main circuit, an electromagnet therein for opening the normally closed contacts in said main circuit after the normally open contacts have been closed 30 by the first mentioned electromagnet.
5. In a system for the purpose described, in combination, a normally open main circuit, a clock-controlled circuit including electromagnetic means for closing the main 35 circuit, and a clock-controlled circuit having electromagnetic means for opening itself and the said main circuit after the latter has been closed by the first-mentioned means.

In testimony whereof I affix my signature. 40

JAMES W. BRYCE.
